UNITED STATES PATENT OFFICE.

ALMA F. KOCH, OF LOUISVILLE, KENTUCKY.

DESIGN FOR A SPOON.

SPECIFICATION forming part of Design No. 22,526, dated June 13, 1893.

Application filed April 5, 1893. Serial No. 469,239. Term of patent 3½ years.

To all whom it may concern:

Be it known that I, ALMA F. KOCH, of Louisville, in the county of Jefferson and State of Kentucky, have invented a new and ornamental Design for Spoons, of which the following, taken in connection with the accompanying drawings, is a full, clear, and exact description.

My design consists in a souvenir spoon which is typical of the State of Kentucky, and is hereinafter more fully described.

In the drawings Figure 1 is a view of the back, or convex side, of the spoon, and Fig. 2 is a view of the face or concave side thereof.

15 The features of the design include the full length representation of the figure of a woman, clothed in leaves of the tobacco plant, the woman standing on an oblong block and being emblematical of the State of Kentucky.

20 The convex side of the bowl of the spoon is shown in Fig. 1 wherein there are shown at top and bottom hoops, common to whisky bar-

rels, and across the surface is represented a thoroughbred race horse on which a jockey is mounted, while the horse is represented as going at full speed. On the concave side there is shown a substantial reproduction of the coat of arms of the State, including the representation of two men with joined outstretched hands, while underneath their feet is a scroll, and over their heads is a row of stars in the form of an arc of a circle, the whole being shown on the face of a shield.

Having described my design, what I claim is—

The design for a spoon, substantially as shown and described.

In testimony whereof I have hereunto set my hand this 31st day of January, 1893.

ALMA F. KOCH.
